(57) **CLAIM**

I claim the ornamental design for an puppy figure, as shown and described.

DESCRIPTION

FIG. 1 is a front elevational view of a puppy figure, showing my new design, the broken line showing of clothing is for illustrative purposes only, and forms no part of the claimed design;

FIG. 2 is a back elevational view thereof;

FIG. 3 is an enlarged bottom view thereof;

FIG. 4 is a right side elevational view thereof; and,

FIG. 5 is an enlarged top view thereof.

The broken lines showing clothing are for illustrative purposes only and do not form part of the claimed design.
